UNITED STATES PATENT OFFICE.

GEORGE E. NORRIS, OF COLUMBUS, OHIO.

MORTISING MACHINE.

Application filed July 13, 1921. Serial No. 484,434.

To all whom it may concern:

Be it known that GEORGE E. NORRIS, a citizen of the United States, residing at Columbus, in the county of Franklin and State 5 of Ohio, has invented certain new and useful Improvements in Mortising Machines, of which the following is a specification.

This invention relates to mortising machines of the rotary cutter type and particularly to the rotary and oscillating cutter type, the primary object of the invention being to provide a mortising machine wherein in an improved arrangement of mechanical parts exists whereby the construction of the 10 machine is generally simplified, as regards similar prior machines, in order that the operation thereof may be easily and conveniently effected, to enable the bit to produce clean cut and well defined mortises and 15 to adapt the machine readily to work on conditions of various kinds.

The present invention has as an outstanding feature the provision of a mortising machine wherein is provided a main stationary 20 frame and a slidable carriage, with which is connected a rotary and reciprocatory cutting bit, and wherein the carriage is provided with a main drive wheel which carries a plurality of concentrically disposed 25 speed gears, which are adapted to selectively cooperate with the bit actuating mechanism, in order that the said bit may be moved back and forth at varying speeds of operation, for 30 the purpose of enabling the bit to efficiently operate in relatively soft or hard woods, to permit the back and forth movement of 35 the bit to be relatively accelerated or retarded and to enable generally the operator of the machine to govern the latter efficiently 40 and rapidly under the varying conditions to which the machine is placed.

Other objects of the invention reside in 45 specifically improving the general construction of mortising machines of this nature, by providing an improved mechanism for effecting the back and forth movement of the bit; in permitting of the adjustment of 50 said mechanism in order that mortises of desired length may be produced; in improving and simplifying the infeed mechanism, which controls the depth of the mortise produced by the bit, and in providing an automatically operating structure for arresting 55 the inward movement of the bit at predetermined positions.

With these and other objects in view, as

will appear as the description proceeds, the invention accordingly consists in the novel features of construction, combinations of elements and arrangements of parts, hereinafter to be specifically described and pointed out in the claims hereunto appended. 60

In the accompanying drawings:

Figure 1 is a side elevation of the improved mortising machine comprising the 65 present invention,

Figure 2 is a vertical longitudinal sectional view taken therethrough on the line 2—2 of Figure 1,

Figure 3 is a horizontal sectional view 70 taken through the machine on the plane indicated by the line 3—3 of Figure 1,

Figure 4 is a detail horizontal sectional view taken on the plane 4—4 of Figure 1 and disclosing more particularly the ratchet 75 operated in feed mechanism,

Figure 5 is a vertical sectional view disclosing in detail the construction of the ratchet operating cam carried by the upper 80 end of the gear shaft,

Figure 6 is a plan view of said cam, the retaining plate therefor being removed from the shaft to disclose underlying structure,

Figure 7 is a detail sectional view setting forth the construction employed in adjustably uniting the bit holder operating link with the slotted crank member, and 85

Figure 8 is a detail horizontal sectional view taken along the line 8—8 of Figure 1 and disclosing the connection between the 90 feed screw and the frame of the machine.

Figs. 9 and 10 are sectional views of detailed parts.

Referring more particularly to the accompanying drawings, the numeral 1 designates the improved mortising machine, comprising the present invention, in its entirety. Essentially the machine includes a main stationary frame 2, which comprises a lower casting 3, which includes spaced side walls 4, the latter serving to permit the casting and the frame generally to be mounted upon the edge of a door 5 or other body in which a mortise 6 is to be produced. To hold the frame rigidly in place upon the edge of the door, the side walls 4 are provided at the opposite ends thereof with threaded openings, in which are adjustably positioned manually operated, threaded binding screws 7, which have their inner ends provided with relatively enlarged heads 8, capable of frictionally engaging with the oppo-

site sides of the door 5 and to exercise sufficient pressure thereon to retain the frame firmly positioned against accidental dislocation upon the edge of the door, or any other equivalent body.

The casting 3 is provided with upstanding bosses 9, in which are positioned and firmly mounted the lower ends of spaced, parallel, upstanding rods 10, which constitute, in effect, a trackway. The upper ends of the rods are suitably received within spaced openings provided in the opposite ends of a horizontally extending top bar 11, which extends parallel with the casting 3, and by its inclusion the frame 2 is rendered substantially rectangular in configuration. If desired, the bar 11 may be provided with a circular handle 12, by means of which the machine may be lifted or manually handled with ease and facility.

Slidably mounted in connection with the frame 2 is a movable frame or carriage 13, which is preferably of skeleton metallic construction and embodies, at the opposite ends thereof, spaced ears or bearings 14, which are adapted to receive the side rods 10, and operate to enable the carriage to be readily moved in the same vertical plane as the frame 2, when it will be securely retained against undue lateral movement with respect to the frame 2. The carriage further includes vertically extending, spaced bars 15, which extend parallel with the rods 10 and lie in the same vertical plane as the frame 2. The lower ends of the bars 15 integrally merge into a substantially curved bottom bar 16, while the upper ends of said bars are integrally formed with a horizontally extending upper bar 17, the opposite ends of the bars 16 and 17 being formed to include the bearings 14 by means of which the carriage as a whole is slidably connected with the frame 2. This construction of the carriage produces one of ample strength and yet exceptionally light in weight. It will be understood that the bars 15 to 17 inclusive may be suitably ribbed and reinforced, so as to enhance the strength thereof. Disposed intermediately of the bars 16 and 17 and formed integrally with the bars 15 is a pair of spaced horizontally extending arms 18, which are centrally apertured to provide registering bearings for the reception of a transversely extending operating shaft 19. This shaft has suitably fixed to one end thereof a main drive gear 20, and this gear, in the present instance, is adapted to be manually rotated by providing the opposite ends of the shaft with crank arms 21, whose outer ends are equipped with handles 22, capable of being manually grasped so that by rotating the same corresponding movement may be imparted to the shaft 19, and thence to the drive gear 20.

The gear 20 is formed to comprise a plurality of concentrically situated gears 23, which rotate in unison with the gear 20 and are employed, as will be hereinafter explained, to impart a variable reciprocating speed motion to the cutting bit 24 of the machine. The arms 18 and the upper bar 17 are provided with registering vertically spaced bearings 25, which receive for rotation the ends of a vertically disposed gear shaft 26. This shaft is provided with a longitudinally extending keyway 27, in which is positioned a key provided in a slideable gear 28, which is adjustable longitudinally of the shaft 26 but is adapted to rotate in unison therewith. The gear 28 is adapted to be manually operated so that the teeth thereof may be selectively engaged with the teeth of any of the concentric gears 23, whereby upon the rotation of the main drive gear 20 rotary movement will be imparted to the shaft 26, and the speed of rotation of said shaft will be regulated by the particular gear 23 in mesh with the slideable gear 28, as it will be clearly understood. Any suitable means may be provided for retaining the gear 28 in its adjusted positions. In this instance the boss of said gear is provided with a laterally extending casing 29, in which is situated a spring pressed ball 30, the latter being adapted to be forced into engagement with depressions provided in the shaft 26, which depressions are situated to register with the concentric gears 23 and thus operate in conjunction with the ball 30 to adjustably retain the slideable gear in its various operating positions.

Fixed to the upper end of the shaft 26 at a point above the keyway 27 is a worm 32, which is located to mesh with a worm gear 33, the latter being fixed upon a transversely extending countershaft 34. To effect the rotatable support of the shaft 34, the upper bar 17 of the carriage is provided with a bearing 35, in which the inner end of the countershaft is rotatably received, the worm gear 33 being disposed immediately adjacent to the said bearing 35. The outer portion of the shaft 34 is suitably supported by means of a substantially L-shaped bearing bracket 36, whose horizontally extending arm is connected as at 37 with the upper part of one of the vertical bars 15 of the carriage, while the vertical arm of the bracket 36 is suitably connected as at 38, with a lateral horizontally projecting ear 39 also integrally formed with one of the bars 15. It will thus be understood that the bracket 36 in combination with the bearing 35 will serve to provide a substantial support for rotatably receiving the countershaft.

Mounted upon the outer end of the countershaft is a crank member 40, which includes a longitudinally extending slotted

guide 41 in its outer surface. The member 40 is eccentrically connected with the outer end of the countershaft 34, and is adapted to rotate in unison with the said shaft. As 5 shown more particularly in Figure 7 the guide 41 is equipped with an internally located nut 42, which is retained in place by means of spaced longitudinally extending flanges 43, which overlap the guide 41 and 10 produce therebetween a slot 44. In conjunction with this structure a bushing 45 is provided, which includes an annular collar 46, arranged to be engaged with the outer surface of the member 40, and the said bushing 15 further includes an outwardly projecting stud 47, and an inwardly projecting stud 48, which is slidably received within the slot 44. The said bushing is provided with an internal bore, in which is positioned the 20 shank of a screw 49, the latter being provided at its outer end with an enlarged head 50, which is designed to engage with the outer end of the stud 47, and is spaced from the collar 46 to provide a construction 25 whereby one end of a bit holder oscillating link 51 may be adjustably and swivelly secured in conjunction with the crank member 40. It will be seen that when the head 50 and the collar 46 are normally spaced, the 30 end of the link 51 will be securely confined therebetween, so that upon the rotation of the crank member oscillatory back and forth motion may be imparted to the link 51. The throw of the link may be regulated by adjusting the bushing 45 and cooperating structure longitudinally of the crank member 40, as it will be apparent that when the crank arm is moved away from the axis of the crank member, the throw of said link 40 will be lengthened and vice versa, the link construction gives uniform travel of oscillating arm 53.

Manifestly, by tightening the screw so 45 that its shank end will be threaded into the bore of the nut 42, a sufficient frictional pressure may be exercised upon the bushing 45 to retain the latter in any given position of adjustment with respect to the crank arm, thus when the screw is tightened the nut will 50 be drawn toward the inner surface of the spaced fingers 43, while the bushing will have its collar 46 pressed firmly against the outer surface of said fingers, a construction being thus provided whereby the throw of 55 the link may be conveniently regulated. Back and forth movement of the link or pitman 51 controls the extent of movement of the bit 24 and accordingly governs the length of any given mortise, or if and for convenience in adjusting the machine, the crank member has its outer surface provided with 60 graduations 52 with which the marked center of the bushing may be registered, thus enabling an operator to accurately set the 65 machine so that a mortise of desired length

may be readily produced. To transmit the motion of the link or pitman 51 to the bit 24, the present invention provides an oscillatory bit operating member 53. This member is provided centrally with an enlarged 70 hub 54, which has its bearings rotatably positioned around the operating shaft 19, and is confined between the arms 18 of the carriage, the upper portion of the said operating member terminating in an angularly 75 disclosed arm 55, to the upper end of which is swiveled, as at 56 the outer end of the link 51. It will thus be manifest that the oscillation of the link, effected by the crank member 40, will result in imparting similar 80 oscillation to the member 53, and that the extent of oscillation of said member may be varied and regulated by the throw imparted to the link 51 through the mechanism previously described.

The member 53 beneath the hub 54 is provided with an integral downwardly disposed extension 57, which is adapted to oscillate between the side bars 15 of the carriage. This extension terminates at its lower end in a horizontally extending shelf 58, which is provided with a downwardly extending sleeve 59, the latter being received within an arcuate slot 60 formed in the lower bar 16 of the carriage. It will be observed that this bar is of curved construction and constitutes a portion of a circle, whose center is defined by the axis of the operating shaft 19, which axis is also the rotatable axis about which the member 53 is 90 permitted to oscillate. The presence of the slot 60 serves to generally strengthen the construction of the member 53 by preventing undue oscillation or vibration thereof and produces a tool which will operate 95 evenly and uniformly with an absence of undue vibration. The extension also includes a second sleeve 61, in which is slidably positioned a bit holder 62. This holder is provided with a longitudinally extending opening in which is positioned the reduced 100 upper end 63 of the bit 24, the extreme upper end of said bit shaft being provided with a collar and balls for end thrust and retaining nuts 64, by means of which the said bit may be securely yet detachably retained in conjunction with the holder.

The extension 57 is provided with a vertical slot 65, in which is positioned the offset lower end 66 of the holder 62, and in this instance the said end 66 is provided with an antifriction roller 67, which is adapted to be received within an arcuate slot 68 formed in a web 69, the latter constituting an integral bar of the carriage 13, and being situated immediately above the bar 16. It will be apparent that the holder is slidably mounted within the sleeve 61, and is supported by the roller 67, which operates in a curved slot 68. The curvature of the slot 68 is opposed 110

to that of the slot 60, and thus an arrangement is provided whereby the bit will be enabled to reciprocate when in operation, so that the lower end thereof will produce a mortise which will possess a straight bottom wall instead of a curved or segmental wall, as is the case when the bit oscillates without reciprocating. The reciprocating bit has the advantage over the type which merely oscillates in that it merely cuts the door 6 to the required depth necessary to receive a lock or latch casing, and avoids cutting the door excessively or unnecessarily. The bit shank is provided with a keyway 70, which receives a key or the like provided in a spur pinion 71. This pinion is adapted to mesh with the outer gear 72 of the concentric gears provided upon the main drive gear, as is clearly shown in Figure 2. By this construction of the machine, it will be seen that in operation the stationary frame will be clamped to the work by means of the screw 7. Then, by manually rotating the handles 22, rotation will be imparted to the operating shaft 19. From this shaft motion is transmitted to the main drive gear and thence by reason of the gear 71 to the bit shaft 24, causing the rotation of the latter. Oscillating back and forth motion is then imparted to the bit automatically so that a mortise of desired length may be produced. This back and forth motion has been provided by reason of the gears 23, which serve to drive the gear shaft 26 and through the medium of the worm gearing 32 and 33 rotary motion is imparted to the countershaft 34 and its fixed crank member 40. From the crank member 40 oscillatory motion is imparted to the bit operating member 53 by the link 51, and the extent of oscillation of the member 53 and the consequent length of a mortise may be regulated by the provision of the adjustable bushing 45. It will be seen that the oscillation of the member 53 causes back and forth motion to be imparted to the bit when the latter is in the state of rotation, and the oscillatory motion of the member 53 is transformed so as to impart reciprocatory motion to the bit by reason of the slidable holder 62 and the slot construction 68 provided therefor in the web 69 of the carriage. In order to permit of the regulated infed of the bit in the process of forming a mortise, the upper end of the gear shaft, as shown in Figures 5 and 6, is provided with a cam 73, which is capable of rotating in unison with the shaft 26 when the latter is revolving in a specified direction. This cam is adapted to oscillate a lever 74, the said lever being pivotally received upon the upper bar 17 of the carriage 13, and the hub 75 thereof which is centrally disposed, is adapted to be positioned about the upper end of a feed screw 76, which is rotatably carried by the carriage and disposed vertically thereof,

the upper end of said screw serving as a pivot for the reception of the lever 74. The under part of the lever is provided with a fixed depending projection 77 against which the free end of a coil spring 78 is disposed to engage, the opposite or fixed end of the spring being mounted in connection with a stationary part of the carriage, the normal tendency of the spring being to maintain the outer or free end 79 of the lever in engagement with the cam 73, whereby upon the rotation of said cam, through the medium of the gear shaft, oscillation will be imparted to the lever. The upper end of the feed screw 76 is in this instance provided with a fixed ratchet wheel 80, and the upper surface of the lever 74 is equipped with a casing 81, containing slidable dogs 82 and 83, the same being forced outwardly of the casing by means of an interposed spring 84. The dog 82 is, by reason of the spring 84, normally maintained in engagement with the teeth of the ratchet, and it will be apparent that as the lever 74 oscillates in responding to the action of the cam 73 and the spring 78, intermittent rotary motion will be imparted to the feed screw 76. The carriage is also provided with a spring pressed plunger 85, which engages with the teeth of the ratchet wheel to prevent the latter from rotating when the dog 82 is being moved to a gripping position. It will also be observed that the cam 73 will rotate with the gear shaft in but one direction. Thus the hub of the cam is provided with a substantially wedge shaped socket 86, in which is positioned a roller 87, the latter being so located that when the gear shaft revolves in an anti-clock-wise direction, the roller 87 will be forced into the narrow portions of the socket 86, enabling the gear shaft to be connected with the cam for rotation in unison therewith, reverse motion, however, of the gear shaft will automatically cause the cam to be freed from rotary connection with the gear shaft.

One of the rods 10 is formed to include a fixed inwardly extending bracket 88, which includes a vertical opening 89 adapted to slidably receive the lower threaded end of the feed screw 76. The said bracket is further provided with a bore 90 closed at its outer end by means of a threaded plug 91, and adapted to receive a longitudinally movable stem 92. This stem is provided with a fixed collar 93 against which one end of a spring 94 engages, the other end of the spring being disposed to engage with the plug 91, so that the normal tendency of the spring will be to force the stem inwardly, in order that its extreme inner end may be positioned in engagement with the threads of the screw 76. The outer end of the stem passes through the bore provided in the plug 91, and is equipped with a knob 95. Said knob is pro-

vided with a projection 96, which is capable of engaging with a fixed enlargement 97 provided upon the plug 91. It will be manifest that when the knob is withdrawn and rotated so that the projections 96 and 97 are in registration, the inner end of the stem will be withdrawn from engagement with the feed screw. However, when the stem is positioned as disclosed in Figure 8, the feed screw will be engaged so as to regulate downward movement of the carriage and consequently the bit carried thereby. Thus, when the feed screw is operated through the medium of the ratchet mechanism an intermittent infeed movement will be imparted to the bit, whereby a mortise of desired depth may be produced.

The infeed movement of the machine may be automatically curtailed by providing the main frame with a fixed vertically disposed bar 98, which is suitably graduated to denote inches. Slidably received by this bar is an adjustable stop lug 99, which through the medium of a set screw 100 may be adjusted longitudinally of the bar 98 and retained in various set positions of adjustment thereon. The lug 99 is so disposed that the dog 83 will engage therewith when the carriage has moved downwardly a predetermined distance. It will be seen that the lever 74 oscillates by reason of the cam 73, and consequently since the lug 99 is fixed and can not rotate, the same will engage with the spring pressed dog 83 and will retain the lever against movement, holding the end of the same out of engagement with the actuating cam 73. By thus arresting oscillation on the part of the lever 74, it will be apparent that further infeeding of the bit will be precluded. The dog 83 is spring pressed and is provided with a beveled surface in order to permit of proper engagement therewith with the lug 99. To raise the carriage, it is simply necessary to withdraw and rotate the stem 92 so as to register the parts 96 and 97. This withdraws the stem from engagement with the feed screw and allows the carriage to be manually elevated. When elevated to a normal position, the carriage may be retained therein by releasing the stem and permitting the latter to again engage with the feed screw.

It will be seen that by reason of the construction described, the present invention provides a mortising machine which appreciably simplifies and improves the construction of machines hitherto produced for this purpose. The machine is light in weight, can be readily applied to the work and may be operated efficiently under various working conditions encountered in the use of the machine. The machine differs generally from the machines of the prior art by providing improved arrangements of its mechanical parts for the purpose of render-

ing the same more accurate, positive, and to facilitate its control, and to generally reduce its cost both to the manufacturer and user. Attention is particularly invited, however, to the construction of the main drive gear by means of which the speed of operation of the machine may be governed at will and to thus adapt the same to various working conditions, that is, to soft or hard woods, or to bits of varying sizes. Another feature of importance resides in the construction for effecting the oscillation of the bit operating member 53. It will be noted that this construction includes essentially the crank member 40 and the link 51. It will be apparent that when the link 51 is positioned at the point zero on the crank member 40, oscillation on the part of the bit operating member will be precluded, thus enabling the bit to bore a round smooth hole, which is sometimes needed in the operation of machines of this kind. A thrust bearing 101 is provided at the upper end of the bit shaft, and is adapted to receive the wear caused by the forcing of the bit into a mortise.

It will be understood that the invention is not limited in its practical embodiment to the specific construction illustrated and described, but that such modifications thereof may be resorted to without departing from the spirit of the invention, that may be said fairly to fall within the scope of the following claims.

What is claimed is:

1. A mortising machine comprising a frame work, a carriage slidably mounted in connection with said frame work, an oscillatory bit operating member mounted in connection with said carriage, a bit adapted for connection with said member, and a main drive element consisting of a plurality of substantially concentrically disposed gears capable of simultaneously effecting the rotation of said bit and oscillating said member at selected speeds.

2. A mortising machine comprising a frame, a carriage slidably mounted upon said frame, an oscillatory bit operating member mounted in connection with said carriage, a bit mounted in connection with said member, a main drive element mounted for rotation in connection with said carriage and including a plurality of substantially concentrically disposed gears, the outer of said gears being disposed to effect the rotation of said bit, and the remaining gears being selectively cooperative with said bit operating member to impart varying oscillating speeds to said member.

3. A mortising machine comprising a substantially stationary frame, a carriage slidably upon said frame, a bit, a pinion carried by said bit, a rotatable gear element in mesh with said pinion for rotating said bit, means for imparting lateral movement to

said bit including an operating shaft, a plurality of concentrically disposed gears rotatable with said element, and an adjustable gear mounted upon said shaft and capable 5 of being selectively engaged with said concentrically disposed gears to impart varying lateral speeds of travel to said bit.

4. A mortising machine comprising a frame, a carriage slidable upon said frame, a 10 main drive element rotatably supported in connection with said carriage and including a plurality of concentrically disposed gears, a bit, a bit operating member mounted for oscillation in connection with said carriage 15 and adapted to impart lateral travel to said bit, a rotatable crank device capable of being driven at varying speeds by said gears, a link between said device and said bit operating member and serving to oscillate the latter, and a rotatable driving connection 20 between one of the gears of said element and said bit.

5. A mortising machine comprising a frame, a carriage slidable on said frame, a 25 bit, a bit supporting structure, means for

moving said structure back and forth, said means including a plurality of concentrically disposed gears capable of oscillating said structure at varying speeds, and means for effecting the rotation of said bit during the 30 oscillation of said structure.

6. A mortising machine comprising a frame, a carriage slidable on said frame, a rotatably mounted drive element provided upon said carriage, said element being 35 formed to include a plurality of concentrically disposed gears, a bit, a bit operating structure mounted in connection with said carriage and operable to impart lateral movement to said bit, means cooperative 40 with said concentrically disposed gears for oscillating said structure at varying speeds, and a pinion carried by said bit and cooperative with the outer of said gears for effecting the rotation of said bit simultaneously with the oscillation of said structure. 45

In testimony whereof I affix my signature.

GEORGE E. NORRIS.
